UNITED STATES PATENT OFFICE.

CARL R. ALEXANDER, OF RICHMOND, CALIFORNIA.

TABLE.

Application filed April 11, 1928. Serial No. 269,055.

The present invention relates generally to tables and has for its prime object to provide a folding table for use by hotels and like places for banquet purposes. Generally the 5 table comprises a plurality of top sections which may be placed in end to end relationship depending upon the length of table described and a plurality of supporting structure on which the table top sections may be 10 mounted, said supporting structure being foldable.

Another very important object of the invention resides in the provision of a table of this nature which is exceedingly simple in 15 construction, inexpensive to manufacture, strong and durable, having great ability in use, easy to assemble and disassemble, and thoroughly efficient and reliable in use.

With the above and numerous other objects in view as will appear as the description proceeds, the invention resides in certain novel details of construction, and in the combination and arrangement of parts as will be hereinafter more fully described and 25 claimed.

In the drawings:

Figure 1 is a side elevation of a table embodying the features of my invention,

Figure 2 is a top plan view thereof,

30 Figure 3 is an enlarged detail side elevation of one of the supporting structures showing the same extended,

Figure 4 is a top plan view of the supporting structure showing one top leg extended 35 and the other folded, and

Figure 5 is a sectional view taken substantially on the line 5—5 of Figure 3 looking in the direction of the arrows.

Referring to the drawing in detail it will 40 be seen that the numeral 5 denotes a plurality of elongated rectangular top panels which are provided at their ends with substantially transverse flanges 6. The hotel or like place using this table construction may 45 have any number of these panels 5 and they may be furnished in different sizes it being preferable, however, that they all be of equal width.

A plurality of supporting structures are 50 provided for the top panel 5 and since they are all of identical construction one only will be described in detail sufficing to obtain a clear understanding of the construction and utility of all. Referring to one of these supporting structures in detail it will be seen that 55 it comprises a pair of legs 7 connected by

cross bars 8, preferably though not necessarily, two in number.

A bar 9 is disposed across the top ends of the legs 7 and secured to the top cross bar 8. 60 This top bar 9 is wider than the cross bar 8 as is clearly indicated in Figure 4 taken with Figure 3. Flanges 10 are disposed in spaced parallelism on the top board or bar 9 along the longitudinal edges thereof to receive 65 therebetween the flanges 6 as is clearly illustrated in the center portion of Figure 1 when the supporting structure is used between two top panels 5.

However when the supporting structure is 70 used at the end of the table as is indicated to the left or right of Figure 1 it is preferable to rest the table on the two flanges and allow the flange of the panel to extend down along the outermost flange 10 for the purpose of disposing the supporting structure at the end inwardly under the table thereby providing a more convenient structure and a 75 neater appearance.

A pair of top legs are denoted by numerals 80 12 and have lateral bars 14 adjacent their lower ends attached thereto and hingedly connected as at 15 with the lower cross bar 8. Similar lateral bars 16 are secured to the upper ends of the top legs 12 and braced thereto as at 17 and extend inwardly and are hingedly connected as at 18 with the upper cross bar 8. These top legs are hinged so as to swing in opposite direction as is indicated 85 to advantage in Figure 4 and they are disposed adjacent the center of the cross bar 8.

When the supporting structure is disposed 90 between the panels as shown in the center of Figure 1 these props will be swung outwardly so that their lateral bars 14 and 16 are disposed at right angles to the plane of the legs 7 but when the supporting structure to be used at the end the outermost top leg will not be extended outwardly but will be folded out of the way as clearly indicated in Figure 1.

It is thought that the construction, utility 95 and advantages of this invention will now be clearly understood by those skilled in this art and it will be apparent that a table of almost any suitable length may be employed for banquet purposes and the like and the parts thereof are capable of being easily assembled and may be stored away in a minimum amount of space when folded.

The present embodiment of the invention 100 has been disclosed in considerable detail 105 merely for the purposes of exemplification

since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A table structure of the class described comprising a plurality of panels, a plurality of foldable supporting structures under the panel, the supporting structures comprising a pair of legs, cross bars between the legs, a pair of top legs, lateral bars on the top legs hingedly connected with the cross bars, top bars on the upper cross bar for supporting the panel.

2. A table structure of the class described comprising a plurality of panels, a plurality of foldable supporting structures under the panel, the supporting structures comprising a pair of legs, cross bars between the legs, a pair of top legs, lateral bars on the top legs hingedly connected with the cross bar, top

bars on the upper cross bar for supporting the panel, said panels having at their ends depending transverse flanges for disposition in abutting relation to the adjacent top bar.

3. A table structure of the class described comprising a plurality of panels, a plurality of foldable supporting structures under the panel, the supporting structures comprising a pair of legs, cross bars between the legs, a pair of top legs, lateral bars on the top legs hingedly connected with the cross bar, a top bar on the upper cross bar for supporting the panel, said panels having at their ends depending transverse flanges for resting on the top bar, a pair of spaced parallel flanges on the top bar between which the flanges of the top panel may extend.

4. A table supporting unit comprising a pair of legs, a cross bar connecting the legs, a pair of top legs, lateral bars fixed to and extending from the top legs and hingedly connected to the cross bars, a top bar on the upper ends of the first mentioned leg, and spaced parallel flanges extending along the top bar.

In testimony whereof I affix my signature
CARL R. ALEXANDER.
